United States Patent Office

Des. 207,855
Patented June 6, 1967

207,855

HAY BALER

Constantine J. Kermes, Lancaster, Pa., assignor to Sperry
Rand Corporation, New Holland, Pa., a corporation of
Delaware

Filed Sept. 26, 1966, Ser. No. 4,009

Term of patent 14 years

(Cl. D40—1)

FIG. 1.

FIG. 2.

FIG. 3.

FIG. 4.

FIG. 5.

FIG. 1 is a front perspective view taken from one side of a hay baler embodying my new design;

FIG. 2 is a side perspective view thereof taken from the side shown in FIG. 1;

FIG. 3 is a rear perspective view thereof also taken from the side shown in FIG. 1;

FIG. 4 is a side perspective view thereof taken from the side opposite that shown in FIG. 1; and

FIG. 5 is a top plan view of the baler.

The dominant features of my design reside in the full line portions of the drawings.

I claim:

The ornamental design for a hay baler as shown, and described.
